R. W. WUEST

TOY AEROPLANE DEVICE

Filed March 31, 1923

Patented Jan. 13, 1925.

UNITED STATES PATENT OFFICE.

ROLLIE W. WUEST, OF MONROE, MICHIGAN.

TOY AEROPLANE DEVICE.

Application filed March 31, 1923. Serial No. 628,985.

To all whom it may concern:

Be it known that I, ROLLIE W. WUEST, a citizen of the United States, and resident of Monroe, Monroe County, Michigan, have invented a certain new and useful Improvement in Toy Aeroplane Devices, of which the following is a specification.

This invention relates to toy aeroplane devices, but more particularly to those which are propelled by momentum, after being forcibly launched into the air.

Generally stated, the object of the invention is to provide a simple and novel form of toy aeroplane or glider provided with rotating means which will cause the toy to preserve its balance and equilibrium in the air, so that it will glide in the desired manner.

It is also an object to provide a novel and improved device for launching or projecting the toy aeroplane into the air, with sufficient force to cause the toy to glide through the air for a distance.

It is also an object to provide certain details and features of construction tending to increase the general efficiency and the desirability of a toy of this particular character.

To these and other useful ends, the invention consists in matters hereinafter set forth and claimed and shown in the accompanying drawings in which—

Figure 1 is a side elevation of a toy aeroplane or glider embodying the principles of the invention, showing the same in position on the device for launching or projecting the toy into the air.

Figure 2 is a plan of the aeroplane and projecting device shown in Figure 1.

Figure 3 is a perspective, on a larger scale, of the toy aeroplane or glider.

Figure 4 is an enlarged cross section on line 4—4 in Figure 1.

Figure 5 is an enlarged cross section on line 5—5 in Figure 1.

As thus illustrated, the invention comprises the longitudinal body member 1 of any suitable character, and provided at its front end with the fork 2 to receive the disc

3 of paper or pressed board mounted on the pin 4 to rotate in said fork. The wings or planes 5 can be made of paper or other light material, of sufficient strength, and are formed with middle portions 6 which brace the body 1, and which are glued or otherwise secured thereto.

The projecting device comprises, as shown, a gun-shaped body having its barrel 7 formed along the top thereof with a longitudinal groove 8, provided at the rear end 60 with a stock 9, of the desired form and size. A transverse notch 10 is cut into the top of the barrel, across the groove 8, and a cam-shaped trigger 11 is mounted in position to intersect said notch. Rubber bands 12 are 65 stretched from the front end of the gun into the notch 10, as shown, and by pulling the trigger the rubber bands will be released.

In use, the toy aeroplane is placed in position as shown in Figure 1, with the disc 3 in the groove 8 immediately in front of the notch 10, so that the aeroplane is in position to be discharged. This is accomplished by pulling the trigger 11, so that the cam portion of the trigger will raise the rear end portions of the band 12 out of the notch 10, and the sudden impact of the rubber bands against the rear edge of the disc 3 will project the toy aeroplane forward, and will at the same time spin the disc 3 at a 75 high rate of speed. The toy shoots forward in the air, with the disc 3 rotating at high speed, so that the balance and equilibrium of the toy are maintained as it glides forward 80 in air. The disc can be of any suitable or desired shape, and the rapid rotation thereof 85 keeps the toy from turning over, and keeps it on its course.

The different parts can be made of any suitable or desired materials, it being preferable, of course, to use light materials for the parts of the aeroplane, but the gun may be made of metal or wood or any other suitable material.

It will be seen that the toy aeroplane is 90 essentially a non-self propelling toy aeroplane, as it has no means by which to propel itself, and is dependent entirely upon the momentum given it by the projecting device represented by the toy gun. The disc 3 is a 100 stabilizing device, which is rotatable about a transverse axis, and is also a guiding device, inasmuch as it traverses the guide groove 8 to determine the direction of the toy in the air.

What I claim as my invention is—

1. In a toy aeroplane, a body and wings or planes therefor, and a rotating element mounted to rotate about an axis disposed transversely of the aeroplane and adapted 110 to preserve the equilibrium of the toy in its flight.

- 2
2. A structure as specified in claim 1, said rotating element comprising a disc mounted at the front end of the body, to rotate about the transverse axis, so that the disc is 5 presented edgewise to the air.
3. A structure as specified in claim 1, said body comprising a longitudinal member having said wings or planes disposed transversely thereof, and said rotary means comprising a disc mounted to rotate about the horizontal and transverse axis at the front end of said body.
4. A structure as specified in claim 1, in combination with a projecting device for 15 launching the toy into the air, comprising means to forcibly project the toy into the air, and other means for spinning the rotary means at high speed as the toy is launched into the air.
5. A structure as specified in claim 1, said rotary means comprising a rotary disc mounted to rotate about the horizontal and transverse axis, in combination with a projecting device comprising a guide for said 25 disc, and impact means to engage the rear edge of said disc to project the toy into the air, and to spin the disc at high speed as the toy leaves said projecting device.
6. A structure as specified in claim 1, said 30 rotary means comprising a disc mounted to rotate about the horizontal and transverse
- axis, in combination with a projecting device comprising a longitudinal guide for said disc, rubber band means for projecting the toy into the air, and a trigger for releasing the said rubber band means to cause impact thereof on the rear edge of said disc in a manner to project the toy into the air and rotate said disc at high speed. 35
7. The combination of a non-self propelling toy aeroplane, and a projecting device having means to forcibly project the toy into the air, said toy having rotary stabilizing means for the front end thereof rotatable about a transverse axis. 40
8. A structure as specified in claim 7, said toy having rotary stabilizing means at the front end thereof, rotatable about a transverse axis, and said projecting device having means to engage and rotate said stabilizing device, during the forcible projection of the toy into the air, serving also to guide the toy in the desired direction. 45
9. A structure as specified in claim 7, said toy having a disc disposed in the vertical plane at the front end thereof, rotatable about a transverse axis, thereby to stabilize the flight of the toy, and said projecting device having means for causing said disc to rotate about the toy as it is launched into the air. 50

ROLLIE W. WUEST.
